UNITED STATES PATENT OFFICE.

NICHOLAS ZILLIER, OF NEW CASTLE, DELAWARE.

IMPROVEMENT IN SCREW-PLATES.

Specification forming part of Letters Patent No. 56,663, dated July 24, 1866.

To all whom it may concern:

Be it known that I, NICHOLAS ZILLIER, of New Castle, in the county of New Castle and State of Delaware, have invented a new and useful Improvement in Screw-Plates; and I do hereby declare that the following is a full, clear, and exact description thereof, which will enable others skilled in the art to make and use the same, reference being had to the accompanying drawings, forming part of this specification, in which—

Figure 1 is a side view of my improved screw-plate. Fig. 2 is a detail view of the same, taken through the line $x\ x$, Fig. 3. Fig. 3 is a longitudinal section of the same, taken through the line $y\ y$, Fig. 1.

Similar letters of reference indicate like parts.

My invention has for its object to furnish an improved screw-plate for cutting the threads upon screws, simple in construction, and easily adjusted so as to cut the threads upon screws of any desired size without changing the dies; and it consists of a screw-plate formed by combining with the two-handled plate a die-holder, dies, spring, and cap, the whole being constructed and arranged as hereinafter more fully described.

A is the plate, which is made with two handles, a' and a'' , as shown in Fig. 1. Through the center of this plate is formed a hole. This hole is cut out in the shape represented in Fig. 2—that is to say, in the interior edge of the plate A, forming the sides of the hole, are formed three shoulders, a^3 , the said edge curving gradually from the top of one shoulder to the bottom of the next one, forming three circular inclined planes, a^4 , as shown in Fig. 2.

B is the die-holder, which is a plate of such a size as to cover the hole through the plate A, and has a circular projection, b' , on its inner side, of such a size as to fit into the hole through the plate A between the shoulders a^3 , as shown in Fig. 2. This die-holder B has a circular hole through its center, through which the screw upon which the thread is to be cut enters, and into which the cutting-dies project.

The height of the projection b' is equal to the thickness of the plate A, so that the face of said projection may be flush with the side of the said plate A, as shown in Fig. 3.

The outer edge of the face of the projection b' is channeled, so as to form a circular shoulder for the reception of the spring C. The surface of the projection is also grooved radially

for the reception of the three cutting-dies D. The grooves are of a depth equal to the height of the projection b' , so that the breadth of the dies D may equal the thickness of the plate A.

The rear ends of the dies D are beveled to correspond to the inclination of the inclined planes a^4 . The upper edges of said dies are also notched for the reception of the open spring-ring C.

E is a cap of sufficient size to cover the hole through the plate A. The cap is secured to the die-holder B by screws F, which screw into the projection b' , as shown in the drawings, holding the dies D and spring C securely in place, as shown in Fig. 3.

Upon one edge of the die-holder B and of the cap E are formed ears G and H, in which are formed circular slots, as shown in Figs. 1 and 3. In the plate A is also formed a shorter circular slot, as shown in Fig. 2.

I is a bolt passing through the three slots, the body of which is so formed that it cannot turn in the slot in the plate A. By this bolt and by the thumb-nut J the die-holder B and the cap E may be clamped fast to the plate A in any desired position.

Upon the edge of the die-holder B is formed an index or pointer, K, which indicates, by means of the graduated scale L, when the dies have been moved into the proper position to cut a screw of any desired size.

The dies are adjusted for cutting screws of different sizes by revolving the die-holder B and cap E in one or the other direction. By revolving these parts in one direction the dies D are forced forward by their rear ends pressing against the inclined planes a^4 , enabling the tool to cut the threads upon a small screw. By revolving them in the other direction the dies are drawn inward by the action of the spring C, enabling the tool to cut the threads upon a large screw, the index K and scale L enabling the dies to be so set as to cut the screw of the exact size required.

I claim as new and desire to secure by Letters Patent—

An improved screw-plate formed by combining with the two-handled plate A the die-holder B, the dies D, the spring C, and the cap E, the parts being constructed and arranged substantially as herein described, and for the purpose set forth.
